Attorney

UNITED STATES PATENT OFFICE.

H. FRED COX, OF GRAND RAPIDS, MICHIGAN, ASSIGNOR TO H. F. COX COMPANY, OF GRAND RAPIDS, MICHIGAN, A CORPORATION OF MICHIGAN.

FILING DRAWER.

Application filed August 17, 1925. Serial No. 50,590.

This invention relates to a drawer construction having particular reference to the construction of filing drawers wherein various papers or other memoranda are adapted to be filed for convenient access whenever desired. It is an object and purpose of the present invention to construct a novel follower for drawers of this character which may be readily operated back and forth from the front end of the drawer and which at all times maintains a fixed angle to the vertical. A further object of the invention is to provide the front end of the drawer at its rear side with a novel means whereby the papers filed in the drawer are not pressed against the rear side of said front end but the foremost paper, card or other material filed is held a distance back from the front end of the drawer and at a convenient angle so that it is always readily seen and adapted for ready inspection. A further object of the invention is to provide in this construction a pocket directly back of the front end of the drawer in which various indicating cards of smaller size or other indicia relative to or informative of the contents of the drawer may be placed. All of these novel features are attained by structure which is readily made in an economical manner from sheet metal chiefly, whereby economy in manufacture is also made a feature of the invention.

For an understanding of the invention by means of which these ends are attained, reference may be had to the following description taken in connection with the accompanying drawing, in which,

Fig. 1 is a longitudinal vertical section through the filing drawer made in accordance with my invention.

Fig. 2 is an elevation with a part in section, showing the operating crank for moving the follower back and forth in said drawer, and

Fig. 3 is a vertical transverse section substantially on the plane of line 3-3 of Fig. 1 looking in the direction indicated by the arrows.

Like reference characters refer to like parts in the different figures of the drawing.

The drawer is made of sheet metal and may be of any preferred construction. As shown it includes a base 1, a front end 2 and a back end 2^a, the front end at its vertical and upper edges being turned back

upon itself to make securing lips 3, the purpose of which will later appear. The bottom 1 does not extend the full width of the drawer but at each edge is turned upwardly for a short distance, as indicated at 4, thence horizontally outward, as shown at 5, the sides 6 of the drawer being turned upwardly from the outer edges of the sections 5 and terminating in channel portions 7 with which the drawer guides are associated for maintaining the drawer in a suitable casing. This is a preferred construction of the drawer but the invention is not in any sense limited to this particular construction.

At the front end of the drawer and directly over the bottom 1 a block 8 is located, having a central opening interiorly threaded with which a fitting 9 is associated, the same at its rear end having a reduced extension 9^a exteriorly threaded to pass through the block 8 and make a secure connection, it being understood that an opening is made in the front end 2 of the drawer for the passage of said part 9^a. A rod 10 extends lengthwise of the drawer in the lower part thereof in the trough formed by the base 1 and the vertical portions 4. This rod for the greater portion of its length is provided with a spiral thread of long pitch. The rod at its front end passes through the fitting 9 and is formed at its end with a squared section 11, the fitting at its front end being bored out to make an opening considerably larger than the diameter of the rod. The rod is retained in the fitting 11 by a wire 12 which is seated in complementary grooves made around the rod and in the opening in the fitting through which the rod passes.

The follower comprises a sheet metal plate 13 which extends downwardly and forwardly at an angle to the vertical to the bottom of the drawer being formed at its lower edge with a horizontal rearwardly turned flange 14 which rides against the upper side of the base 1 or in close proximity thereto. A block 15 of metal is permanently secured to the rear side of the follower above the flange 14 and has an opening therethrough threaded to correspond with the thread on the rod 10 so that by rotating said rod 10 the follower may be moved back and forth in the drawer in accordance with the direction of rotation of the rod. The rod is

adapted to be rotated by a crank 16 (see Fig. 2) which is provided with a socket 17 to fit over the squared end 11 of the rod.

Spaced a short distance back of the front end 2 of the drawer is a plate of sheet metal 18 which at its vertical sides and at its upper edge is turned forwardly making flanges 19, the same terminating in out-turned flanges 20 received within and clinched to the front end 2 by the lips 3 previously described. The plate 18 extends downwardly in the drawer to a distance above the bottom sections 5, is then turned to the rear horizontally for a short distance, as indicated at 21, thence bent upwardly and to the rear at an angle to the vertical, as shown at 22, then provided with a return bend 23 and continued downwardly and forwardly, as indicated at 24, to a short distance above the bottom sections 5, and then turned forwardly making a horizontal bottom portion 25 as shown. This provides a pocket between the plate 18 and the section 22 for the reception of various indicia respecting the contents of the drawer, the actual contents filed within the drawer to which reference is to be made being held between the follower 13 and the back section 24. Said follower and section 24 are located at substantially the same angle to the vertical and parallel to each other.

A follower of this type does not change its angular position with respect to the drawer or the contents filed therein and it may be moved backward or forward very quickly and easily. This is a valuable feature, the follower being much more simple to operate for change of position and being much more readily changed small distances in position.

The rear side of the pocket described serves as a stop to prevent the front papers, cards or the like filed in the drawer being pressed closely against the back side of the front end of said drawer in which case access to or examination of said papers or other material is not easy and, particularly, it is liable to cause overlooking of such front-located papers or other material filed, in a great many instances; while with the present construction the material filed at the front end of the drawer is not only located a distance back of the front of the drawer but is held at a convenient angle so that one may readily see what such matter filed is.

The invention described is comparatively simple so far as structure is concerned but is very useful in the filing art. Various

changes in minor detail of construction may be made without departing from the invention defined in the appended claims and it is to be considered that all such changes or differences in detail of construction different than the specific disclosure made, but which come within the scope of the claims, are comprehended by this invention.

I claim:

1. In combination with a drawer having a bottom, sides and front and rear ends, of a follower located in the drawer and inclined rearwardly, means for moving the follower to different positions in said drawer, and a member attached to the rear side of the drawer front formed with a portion located a distance back of the rear of the front having its rear side paralleling the plane of the follower, substantially as described.

2. In combination with a drawer having a bottom, sides and front and rear end, of a metal member attached to the rear side of the drawer front formed with a vertical portion from which a section is turned to the rear for a short distance at its lower end, thence bent upwardly and to the rear at an angle and then back upon itself and thence bent forward horizontally toward the rear side of the drawer front whereby a pocket is made located back of the drawer front, substantially as described.

3. In combination with a drawer having a bottom, sides and front and rear ends, of a follower located in the drawer inclined to the rear, and a member attached to the rear side of the drawer front formed with a pocket open at its upper side, said pocket at its rear side being inclined to the rear to lie in a plane substantially parallel with the plane of the follower, substantially as described.

4. In combination with a drawer having a bottom, sides and front and rear ends, of a follower located in the drawer, means for holding the same in a plane inclined to the rear, means for moving the follower to different positions in said drawer, a member attached to the rear side of the drawer front and formed with a pocket open at its upper side, the rear wall of said pocket being inclined to the rear and its upper edge being spaced a distance back of the rear side of the drawer front, said rear side of the pocket being in a plane substantially parallel to the plane of the follower.

In testimony whereof I affix my signature.

H. FRED COX.
